UNITED STATES PATENT OFFICE.

GEORGE STIEFEL, OF CHICAGO, ILLINOIS.

BUNG-CLOSURE.

1,107,723.

Specification of Letters Patent. Patented Aug. 18, 1914.

Application filed June 12, 1913. Serial No. 773,183.

To all whom it may concern:

Be it known that I, GEORGE STIEFEL, a subject of the Emperor of Germany, and a resident of Chicago, Cook county, Illinois, 5 have invented certain new and useful Improvements in Bung-Closures, of which the following is a specification.

The essential object of this invention is to provide a bung-closure which, in certain 10 respects, is an improvement upon and addition to the bung-closure which is shown and described in my pending application for patent filed August 8, 1911, Serial No. 643,002. The closure shown and described 15 in the aforesaid application is particularly adapted for use in connection with the head of a barrel, whereas the bung-closure shown and described in this application is one which is primarily designed to be applied 20 to a bung-hole which is bored through one of the staves of the barrel at or near the bilge.

In the drawings, Figure 1 is a top plan view looking toward the barrel, part of the 25 outer casing being broken away; Fig. 2 is a view similar to Fig. 1, the movable parts being shown in dotted lines and in a different position from that depicted in Fig. 1; Fig. 3 is a sectional view taken on the line 30 3—3, Fig. 1; Figs. 4 and 5 are sectional views of the bottom cap, Figs. 4 and 5 being in inverted position as compared to Fig. 3; and Fig. 6 is a view of the bung-closure with the device for operating the valve applied thereto, some of the parts being shown 35 in section and some in elevation.

The casing 1 is cylindrical in shape and is provided with external screw threads 2 adapted to be screwed into the bung-hole of 40 the barrel. The bottom cap 3, the construction of which will hereafter be more specifically described, may either be screwed upon the bottom of the casing or may simply be driven into position, this last-named 45 construction being the one shown in the drawings. The circular closure plate or valve 7 provided with the aperture 8 is placed above the bottom cap 3. The plate bears a pin 17 which is received within the 50 slot 16 upon the arm 13. To this arm 13 is connected the boss 14, within which there is formed the hexagonal aperture 15. It will be noted that up to this point the invention 55 has been described using the same reference numerals as those employed to denote like parts in the aforesaid application, Serial

No. 643,002, wherein the construction and operation of said parts are more specifically described.

Projecting outwardly from the casing 1, 60 and preferably formed integral therewith, are large ears or plates 18. Since the device in its completed form is usually several inches in diameter, the particular stave which is provided with the bung-hole might 65 be unnecessarily weakened by the boring of a large bung-hole. In the drawings, a fragment of the stave 19 which is bored is shown in Fig. 1 of the drawings, and the ears or projecting plates 18 protrude outwardly 70 from the bung-closure beyond the edge of that stave. Said members 18, therefore, will rest upon and engage those staves which are respectively on one side or the other of the stave 19 and in this manner will serve to 75 reinforce said stave and prevent the same from caving in or breaking in case the weight of the barrel should happen at any time to rest upon the bored stave 19.

The casing 1 is provided with the perforation 20 which extends vertically therethrough, and within said perforation 20 the boss 14 is received, there being preferably a shouldered seat 21 in the perforation 20 to receive the boss 14. The circular 85 closure plate 8 is directly beneath and in engagement with the boss 14 and arm 13, and said plate is caused to revolve when the arm 13 is rotated. Said arm is adapted to be carried from the position shown in Fig. 90 1 to that depicted in Fig. 2. When the parts are in the position shown in Figs. 1 and 3, the perforation 8 in the rotatable plate 7 will register with the opening 20, but when the parts are in the position of 95 Fig. 2, the rotatable plate will close the opening 20.

The bottom plate 3, as shown in Figs. 4 and 5, is provided with a boss 22 which is preferably screw-threaded on its interior 100 wall, and the ring 23, which is provided with screw-threads upon its outer wall, is adapted to be received within said boss 22. Said ring 23 bears an annular seat 24, and upon this seat rests a ring or web 105 of packing or the like. The screw threads upon the inner wall of the boss 22 do not extend to the top of the boss in Fig. 3 or to the bottom of the boss in Figs. 4 and 5, but at the bottom, Fig. 4, the inner wall of 110 the boss 22 is smooth and the packing 25, therefore, is received between a smooth sur-

face upon the wall of boss 22, and between a smooth surface on the outer edge of the ring 23. As clearly shown in Figs. 4 and 5, the web of packing projects a short distance 5 beyond the ring 23 and the plate or cap 3, and is adapted to press against the closure plate 7 and in this manner to form a tight joint. When the parts are assembled, the central aperture through the ring 23 and the 10 boss 22 is in registration with the aperture 20. When the movable parts are as depicted in Figs. 1 and 3, the aperture 8 will likewise be in registration with the aperture 20 and with the aperture through the ring 15 23; but when in the position shown in Fig. 2, the plate 7 will close the passageway through the device. Any liquor or liquid which may be within the barrel may press upon the under surface of the plate 7, but 20 none of the liquid can escape because of the tight joint resulting from the engagement of the packing 25 upon the rotatable plate 7.

A wrench with an ordinary hexagonal head may be used to open and close the 25 valve, but since it is desirable to have such wrench used in conjunction with some kind of a filling head, a device like that shown in Fig. 6 may be employed. In said figure there is shown a handle 26 which is attached to the casing 27. The casing is of 30 just the proper diameter to be received within the aperture 20, and at its lower end bears the hexagonal head 28. The pipe 29 is secured in any suitable manner within the casing 27, some kind of a joint being used by 35 which the pipe 29 need not turn even though the handle and the casing are turned. If so desired a pipe may extend downwardly from the hexagonal head 28 to reach the bottom 40 of the barrel, but such a pipe, which is not shown in the drawings, would have to be removed before the valve could be closed.

The ring 23 is preferably provided with 45 slots or notches 30 to afford a grip for whatever tool may be used to screw or unscrew the ring 23.

It is obvious that many changes in the details of construction and arrangement of

parts may be made without departing from the scope of the invention or of the various 50 claims.

I claim as my invention:

1. A bung-closure comprising a casing, a bottom member received therewithin, a boss upon said bottom member, said casing and 55 said boss being provided with registering apertures, a ring adapted to be secured within said boss, a packing adapted to be retained between the ring and the boss, a rotatable valve disposed between the top of 60 said casing and said boss, said valve being normally in engagement with said packing, and means to rotate the valve.

2. A bung-closure comprising a casing, a bottom member received therewithin, a boss 65 upon said bottom member, said casing and said boss being provided with registering apertures, a ring adapted to be secured within said boss, a packing adapted to be retained between the ring and the boss, those 70 surfaces of the boss and of the ring which engage said packing being smooth at the point of engagement, a rotatable valve disposed between the top of said casing and said boss, said valve being normally in engagement with said packing, and means to 75 rotate the valve.

3. A bung-closure comprising a casing having an aperture therethrough, a shouldered seat within said aperture, a bottom 80 member received within the casing and having a packing member in connection therewith, a rotatable valve engaging said packing member and located between said bottom member and said seat, an arm, a boss thereupon, said boss being received within said seat, and means to rotate the arm, thereby to 85 rotate the valve.

In testimony whereof I have hereunto affixed my name in the presence of two wit- 90 nesses.

GEORGE STIEFEL.
